To all whom it may concern:

Be it known that I, Louis Elowsky, a citizen of the United States, residing at Brooklyn, in the county of Kings and State of New York, have invented a new, original, and ornamental Design for a Jacket, of which the following is a specification, reference being had to the accompanying drawing, forming part thereof, wherein—

The figure is a front view of a jacket showing my new design. The back of the jacket is conventionally plain.

The characteristic feature of my design resides in the combination on a loose coat jacket having patch pockets of cow cartoons applied thereto in association with buttons having characters thereon, as shown.

I claim:

The ornamental design for a jacket, substantially as shown and described.

LOUIS ELOWSKY.
